UNITED STATES PATENT AND TRADEMARK OFFICE
CERTIFICATE OF CORRECTION

PATENT NO. : Des. 317,621

Page 1 of 3

DATED : June 18, 1991

INVENTOR(S) : Summer R. Stone

It is certified that error appears in the above-identified patent and that said Letters Patent is hereby corrected as shown below:

Sheet 1 of 9, consisting of Fig. 1, should be deleted to appear as per attached sheet.

Sheet 8 of 9, Consisting of Fig. 8, should be deleted to appear as per attached sheet.

Signed and Sealed this
Twelfth Day of January, 1993

Attest:

DOUGLAS B. COMER

Attesting Officer

Acting Commissioner of Patents and Trademarks
